UNITED STATES PATENT OFFICE.

JOHN VON DER KAMMER, OF CHICAGO, ILLINOIS.

DESIGN FOR A SEAL-PIECE.

SPECIFICATION forming part of Design No. 21,161, dated November 10, 1891.

Application filed January 10, 1891. Serial No. 377,331½. Term of patent 14 years.

To all whom it may concern.

Be it known that I, JOHN VON DER KAMMER, a subject of the Emperor of Germany, residing at Chicago, county of Cook, and State 5 of Illinois, have invented and produced a new and original Design for Seal-Pieces, of which the following is a clear, full, and exact specification.

My new design is illustrated in the accompanying drawings, wherein—

Figure 1 is a front view of the seal-piece, and Fig. 2 is a horizontal cross-section through the same.

Like parts are indicated by the same letters 15 in both figures.

A is a stem somewhat enlarged; B B, the limbs projecting from the same, substantially circular in cross-section; C, the thin web connecting the same, and D the illuminator; E E, 20 the conductors connected therewith and embedded in the limbs of the seal-pieces.

It will be understood that this seal-piece is the piece which contains the leading-in conductors of the incandescent lamp and which

is designed to be placed inside of the seal 25 within the lamp after the illuminator has been attached to the inwardly-projecting ends of the leading-in conductors. Incandescent electric lamps are used so extensively and in such conspicuous positions that every detail 30 of the lamp must receive attention with respect both to its utility and its artistic appearance. These seal-pieces have been made of various shapes; but I have designed the herein-disclosed shape as being the most artistic form or design for the same. It consists, substantially, of the Y-shaped piece composed of the stem and branches and the thin web connecting the two branches, and it is of course preferably made of glass. 40

I claim—

The design for a seal-piece for incandescent lamps, substantially as shown and described.

JOHN VON DER KAMMER.
